Patented Aug. 12, 1975

236,271

PORTABLE CALCULATOR OR THE LIKE

Andrew Herczog, Painted Post, N.Y., assignor to
Corning Glass Works, Corning, N.Y.

Filed Apr. 8, 1974, Ser. No. 458,649

Term of patent 14 years

Int. Cl. D18—01

U.S. Cl. D26—5 C

Fig. 1

Fig. 2

Fig. 3

Fig. 4

Fig. 5

FIG. 1 is an oblique view of my new design of a portable calculator.

FIG. 2 is a front elevation of my new design of a portable calculator.

FIG. 3 is the bottom view of the calculator of FIG. 2.

FIG. 4 is the left end view of the calculator of FIG. 2.

FIG. 5 is the right end view of the calculator of FIG. 2.

The broken line disclosures shown in FIGS. 1, 2, and 3 are for illustrative purposes only and form no part of the claimed design.

I claim:

The ornamental design for a portable calculator or the like, as shown and described.
